CARD INDEX SYSTEM

Max Theimer, West Point Pleasant, N. J.

Application January 23, 1936, Serial No. 60,416

18 Claims. (Cl. 129—16.5)

This invention relates to certain improvements in cards for filing devices to facilitate and shorten the search for any desired card within a card system.

5 Ordinary filing cards are clumsy to handle in searching for a particular card. One card after another has to be moved along between the finger tips to enable the searcher to see their top lines which generally contain the key to the information on the cards. There are a number of complicated and expensive devices to facilitate the search for cards, but my device is simple and inexpensive.

10 My invention comprises couplings which are shaped out of or attached to each card. Where cards are arranged to stand vertically, which is the most usual case, the coupling device causes the rear card of a stack, when raised, to become automatically attached to the next card in front 15 and to raise said front card. Said front card in turn attaches itself to the next card in front of it, and this latter card being raised automatically continues this action forward until the consecutive cards form a chain with their top 20 lines arranged in step fashion, displaying simultaneously the headings on all the cards in the stack. The cards of the stack become disengaged when lowered into their original positions, and the desired card, now found, may be taken 25 from the stack, if required, by pushing it away from the card in front and then lifting it out. The card is returned by simply pushing it down into its predetermined position in the stack without regard to the coupling device.

30 Other objects and advantages will become apparent upon further study of the description and drawing, in which:—

Fig. 1 is a front elevation of one type of my cards shown in a stack in extended position, said 35 type having two small windows.

Fig. 2 is a section taken along the line 2—2 of Fig. 1.

Fig. 3 is a side elevation of a stack of cards, of the type of Fig. 1, shown in unextended position.

Fig. 4 is a partial section taken as Fig. 2 showing the upper portions of two of the cards in extended position to a large scale.

Fig. 5 is a front elevation of the upper portion 50 of a pair of cards in extended position of a type having one large window.

Fig. 6 is a fragmental rear elevation of the upper portion of a card of the type of Fig. 5.

Fig. 7 is a partial section to an enlarged scale 55 taken along the line 7—7 of Fig. 5.

Fig. 8 is a partial front elevation of the upper portion of a card of a type having metallic couplings mounted thereon.

Fig. 9 is a partial rear elevation of a corner of a card of the type of Fig. 8.

Fig. 10 is a partial section to an enlarged scale taken along the line 10—10 of Fig. 8.

Fig. 11 is a partial front elevation of the upper portion of a card of a type having readily removable metallic clips or couplings, one of the 10 couplings being removed showing the notch into which it fits.

Fig. 12 is a perspective view to an enlarged scale of the metallic clip used on cards of the type of Fig. 11, and

Fig. 13 is a section to an enlarged scale through the portions of three cards of the type of Fig. 5 at their windows, said cards being shown in unextended position and with their tongues nesting in the flexible sheets.

Referring now to Figs. 1, 2, 3 and 4, cards 14 are each provided with an upper slot 15. Slot 15 is located so that its upper edge coincides with line 16 on the card. Line 16 is so located that there is sufficient space between it and the upper edge of the card to allow a line of typing or label for the card. Slot 15 is formed by cutting a channel shaped slit in the card, with the sides of the slit pointing upward, the material of the card thus set free being bent back at the top of the slot to form a tongue 17, the bend defining the upper edge of the slot. Pasted on the front face of card 14 over slot 15 is a thin sheet 20 of "Cellophane", paper or other flexible material. Below slot 15 is another slot 18 of the same size and shape as slot 15. Slot 18 is formed similarly to slot 15 in that a channel shaped slit is cut in the card with the sides of the slit pointing downward. The tongue 19 is bent forward along the web portion of the channel, the bend of the 25 tongue defining the bottom edge of slot 18. A thin sheet of flexible material 21, similar to that used at slot 15, is pasted on the rear face of card 14 over slot 18. The distance between the top edges of slots 15 and 18 is somewhat greater than 30 the space between line 16 and the top edge of the card.

Ordinarily when the cards just described are not in use, they are set in the usual card filing box or drawer (not shown) in the relative positions shown in Fig. 3. For the best functioning of my system the cards must be set in their receptacle with an appreciable amount of pressure between them. Most filing devices have an adjustable slide therein to press the cards together.

When it is desired to extend the cards, the last card of the stack is pulled upward, its forwardly projecting tongue 19 engaging the rearwardly projecting tongue 17 on the card just in front of it and so on throughout the entire stack until a space at the top of each of the cards is exposed. The distance between tongues 17 and 19 is such that it permits the cards to be exposed above their lines 16 so that one can readily see the headings on all the cards.

Thin sheets of material 20 and 21 prevent tongues 17 and 19 from becoming disarranged, that is for tongue 17 to project forward from the card and tongue 19 to project backward. Said sheets also have the further function that when the cards are in unextended position, the tongue of one card cannot enter the slot opposite it of the adjacent card. For example, when the cards are in unextended position, tongue 17 which extends backward, is opposite slot 15 and would become locked in it were it not prevented from doing so by sheet 20 over the front of slot 15. Sheet 21 prevents tongue 19 from sticking through slot 18 of the card in front, thereby preventing the tongue 19 on one rear card from directly raising two forward ones. Similarly sheet 20 prevents tongue 17 from sticking through slot 15 of the card to the rear, thereby preventing two cards to the front from being similarly raised by one from the rear. In each case more than two next adjacent cards might be raised if the tongues stuck through the slots of more than one card. Sheets 20 and 21 together with the portion of the card between slots 15 and 18 act as a barrier for preventing disarrangement of the tongues from their normal positions on their cards and for preventing the tongues for all positions of the cards in passing from unextended to extended position from engaging the cards beyond the next adjacent card.

Referring to Figs. 5, 6, 7 and 13, there are seen cards of a type that have one large window or slot 22. A tongue 23 projects rearwardly and downwardly at the upper edge of slot 22, while a tongue 24 projects forwardly and upwardly at the lower edge of said slot. A thin sheet 26 of "Cellophane", paper or other flexible material is pasted on card 25 with its upper edge upon the front of the card above tongue 23, and with its lower edge upon the rear of the card below tongue 24. Line 27 is so located that there is sufficient space between it and the upper edge of the card to allow a line of typing or label for the card. The upper edge of slot 22 is just below line 27. The distance between the upper and lower edges of slot 22, which is the distance between tongues 23 and 24, is somewhat greater than the distance between line 27 and the top of the card, so that when the cards are in extended position, they are exposed above their lines 27 for the ready reading of their headings. Lifting up the rear card 25 of the stack causes its forwardly extending tongue 24 to engage the rearwardly extending tongue 23 on the card just in front of it and so on throughout the stack until the headings of all the cards are exposed.

The type of cards shown in Figs. 1 to 4 inclusive has the advantage that very little space on the card is used up for the coupling mechanism, but the stack of cards from front to back when in unextended position tends to occupy more space than a stack of plain cards. On the other hand, the type of cards of Figs. 5, 6, 7 and 13 when in an unextended stack occupy but little

more space than a stack of plain cards because tongues 23 and 24 are enabled to nest in slot 22. Although slot 22 is covered with thin sheet 26, the tongues can nest in said slot because said sheet, which is very flexible, is provided with slack as can be most readily seen in Fig. 13. The middle card in said figure shows what takes place with all the interior cards of a stack of three or more cards.

Figs. 8, 9 and 10 show a type of card using a thin readily flexible sheet metal coupling. Two wide slots or cutout openings 28 are provided in card 31, the top of the slots coinciding with line 29 which is spaced from the upper edge of the card sufficiently to allow a heading to be written for the card. Metal coupling 30 which is mounted on the rear of the card, one at each slot 28, is wider than said slot. See Figs. 8 and 9. The coupling 30 has a lower hook 32 which extends through slot 28 coming in front of the front face of the card and pointing upwardly. On each side of hook 32 is a prong 33 extending through the card and bent up against its front face to hold the lower part of coupling 30 against the rear of the card. Similar prongs 34 are at the top of coupling 30 extending through card 31 and bent down against its front face to hold the upper part of coupling 30 against the rear of the card. Between prongs 34 at the upper end of coupling 30 is hook 35 extending rearwardly and downwardly. In using this type of card, when the rearward card is lifted, hooks 32 on its front face engage hooks 35 on the rear face of the card next in front. The vertical spacing between hooks 32 and hooks 35 is such that when the cards are extended, the headings of the cards are visible.

Figs. 11 and 12 show a type of card also using a thin readily flexible sheet metallic coupling, except that instead of said coupling being located opposite an opening in the card as previously described, coupling 38 is set at a notch 36 in the side of card 37. Coupling 38 is provided at its upper end with two upwardly extending prongs 39 set forward of its front face, and at its lower end with two downwardly extending prongs 40, also set forward of its front face. Between prongs 39 at the upper end of coupling 38 is a rearwardly and downwardly extending hook 41. At the lower end of coupling 38 is a forwardly and upwardly extending hook 42. Coupling 38 is mounted upon the card by sliding it into notch 36, the front face of the coupling coming against the rear face of the card while prongs 39 and 40 come in front of the front face of the card, hook 42 at its lower end fitting in small notch 43 and extending in front of the front face of the card. In using this type of cards, when the rearward card is lifted, hooks 42 on its front face engage hooks 41 on the rear face of the card next in front. The vertical spacing between hooks 41 and 42 is such that when the cards are extended, the headings of the cards are visible.

Instead of having the couplings of thin sheet metal, thin sheet material such as celluloid could be used.

Couplings 30, Fig. 8 are permanently attached to the card, that is the cards are furnished with the couplings already attached. These cards are most suitable where an entirely new file is to be installed. On the other hand couplings 38, Figs. 11 and 12 are especially useful where a card index is already in existence and it is desired to install by construction. A special paper cutter

can be used to make the notches 36 in the side of the card. Once these notches are formed, couplings 38 can be easily slid sideways into place at the notches.

5 While the description and claims refer to cards, I wish it to be understood that the term is to be considered as broad enough to cover other types of sheets such as the large sheets or loose leaf pages used in some filing systems.

10 Further, in some types of filing, the cards are pulled out horizontally or obliquely. My system is suitable here. Where cards are to be displayed horizontally, it is not necessary to pull or spread out only the bottom card, but both the bottom 15 and top cards may be spread out in opposite directions. In horizontal filing, where it is desired to have the cards labelled on the bottom line, it is only necessary to reverse the stack.

While the coupling device has been described 20 as coming near the top of the card, I wish it to be understood that it may be at other locations on the card.

The terms top, bottom, front and rear in the 25 claims are used as relative terms, as in a horizontal filing system for example they may become respectively rear, front, top and bottom. Also the other terms involving position and direction are intended to be relative where such sense 30 is applicable. The term "stack" as used herein is intended to mean either all the cards in a particular group or in sections of the group.

I claim:—

1. A card index system comprising a plurality 35 of cards in a stack, engaging means for the rear of each card at a predetermined distance down from its top, and engaging means for the front of each card at a predetermined distance down from its top, said latter distance being greater than the former distance, the rear engaging 40 means of one card being out of engagement with the front engaging means of the card next to the rear when the cards are substantially at the same elevation, but catching on the latter engaging means when the cards are given such relative motion to each other to cause the succeeding 45 cards from front to back to be at successively higher elevations in sufficient amount.

2. A card index system as claimed in claim 1, in which the difference in distance down from 50 the top of the card of the front and rear engaging means is such that when the cards are moved sufficiently to cause said means to catch, the space exposed on the front face at the top of succeeding cards is suitable for a heading.

55 3. A card index system comprising a plurality of cards held in a stack, hooking means extending to the rear of each card and pointing downward, hooking means extending to the front of each card and pointing upward, the front hooking means being at a distance below the rear hooking means and substantially in line therewith, the rear hooking means of one card being out of engagement with the front hooking means of the card immediately to the rear when the 60 cards are substantially at the same elevation but catching on the latter hooking means when the cards are given sufficient relative motion with respect to each other, such motion being that to cause the succeeding cards from front to back to be at successively higher elevations, said distance 65 being such to allow sufficient of said relative motion before the catching of the hooks to expose enough of the front surface at the top of each card for the display of a heading on the card.

70 4. A card index system as claimed in claimed 3

having a barrier extending between the rear and front hooking means on each card preventing the hooking means from becoming accidentally displaced to the opposite side of the card from that from which said means normally extend, said barrier 5 also preventing hooking means from passing through the next adjacent card into engagement with a card beyond.

5. A card index system comprising a plurality 10 of cards in a stack, each card having one or more portions cut away, fasteners of relatively thin sheet material attached to the cards where cut away, each fastener having a web and oppositely extending hooks, one at the top portion of the web extending to the rear of the card and downward and one at the bottom portion of the web extending to the front of the card and upward, the web of the fastener covering over the portion 15 of the card cut away where said fastener is attached, the rearwardly extending hook of a fastener on one card engaging the forwardly extending hook of a fastener on the card immediately to the rear when the cards are given relative upward motion away from each other, the space 20 between the hooks of a fastener being sufficient to permit enough of said relative motion between successive cards before engagement of the hooks, to expose enough surface at the front top of each card for the display of a heading on the card.

6. A card index system comprising a plurality 30 of cards in a stack, each card having a pair of notches, there being a notch at each of its side edges, a pair of fasteners of relatively thin readily flexible sheet material, each having a web and a pair of oppositely extending hooks, one hook 35 being at the top portion of the web and the other at the bottom portion of the web, guide means at the top and bottom of the web of each fastener for sliding the fastener into position in the notch, the top guide means engaging the upper edge 40 of the notch and the bottom guide means engaging the bottom edge of the notch, said guide means when pinched against the edges of the notch maintaining the fastener in the notch, the top hook of each fastener when mounted on the 45 card extending to the rear of the card and downward and the bottom hook extending to the front of the card and upward, the rearwardly extending hook of a fastener on one card engaging the forwardly extending hook of a fastener on the 50 card immediately to the rear when the cards are given relative upward motion away from each other.

7. A card index system as claimed in claim 6 in which the fastener is of greater extent up and 55 down than the distance between the top and bottom edges of the notch, said fastener being mounted at the notch with one face of its web against one face of the card, one of said edges of the notch being provided with a small notch 60 through which the hook at the corresponding portion of the fastener extends to the opposite face of the card from that against which the face of the web of the fastener is mounted.

8. A card index system comprising a plurality 65 of cards in a stack, each card having a slot therein, the material of the card at the bottom of the slot being bent as a tongue to extend upwardly and forwardly and the material of the card at the top of the slot being bent as a 70 tongue to extend rearwardly and downwardly, the forwardly extending tongue on one card engaging the rearwardly extending tongue on the card immediately in front when the cards are given relative upward motion away from each 75

other, the space between the tongues of a card being sufficient to permit enough of said relative motion between successive cards before engagement of the tongues to expose enough surface at the front top of each card for the display of a heading on the card.

9. A card index system as claimed in claim 8 having a thin sheet of flexible material on each card extending over its slot, the upper end portion of the sheet being fastened to the front of the card above the rearwardly extending tongue and the lower end portion of the sheet being fastened to the rear of the card below the forwardly extending tongue.

10. A card index system comprising a plurality of cards in a stack, each card having a pair of slits cut therein one above the other, each slit being in the shape of a channel, the sides of the top channel pointing upward and the sides of the bottom channel pointing downward, the material of the card set free at the upper slit being bent back to form a rearwardly and downwardly extending tongue and the material of the card set free at the lower slit being bent forward to form a forwardly and upwardly extending tongue, the forwardly extending tongue on one card engaging the rearwardly extending tongue on the card immediately in front when the cards are given relative upward motion away from each other, the space between the tongues of a card being sufficient to permit enough of said relative motion between successive cards before engagement of the tongues to expose enough surface at the front top of each card for the display of a heading on the card.

11. A card index system comprising a plurality of cards in a stack, upper engaging means for the rear of each card, lower engaging means for the front of each card at a distance below the upper engaging means, and a barrier extending between the upper and lower engaging means, the lower engaging means of one card being out of engagement with the upper engaging means of the card immediately in front when the tops of adjacent cards are not substantially separated, but engaging the latter engaging means when the cards are given a predetermined amount of relative upward motion away from each other, said barrier preventing the engaging means of one card from catching on with more than one card next adjacent to the front and rear.

12. A card index system as claimed in claim 8 having a thin sheet of flexible material on each card extending over its slot, the upper end portion of the sheet being fastened to the front of the card above the rearwardly extending tongue and the lower end portion of the sheet being fastened to the rear of the card below the forwardly extending tongue, said sheet being thus fastened with sufficient slack therein to permit its flexing for the tongues of the cards to the front and rear to nest in the slot of an intermediate card.

13. A card index system comprising a plurality of cards held in a stack and engaging means between successive cards in the stack for limiting the upward motion away from each other from their position of alignment in the stack of the successive cards, said engaging means having its cooperating parts disconnected from each other

when the cards are in substantial alignment, the allowable length of said motion being sufficient to expose predetermined portions of successive cards.

14. A card index system comprising a plurality of cards held in a stack, and engaging means between successive cards in the stack carried by the cards themselves for limiting the upward motion away from each other from their positions of alignment in the stack of the successive cards, the allowable length of said motion being sufficient to expose predetermined portions of successive cards, the engaging means between successive cards being out of engagement when the cards are substantially in alignment.

15. A card index system comprising a plurality of cards in a stack, and a pair of tongues for each card formed of the material of the card, the card being cut to free material, said material being bent out to form the tongues, one tongue extending rearwardly from the card and pointing downward and the other tongue at a space below the former tongue extending forwardly from the card and pointing upward, said tongues extending across the card for a substantial portion of its width, the forwardly extending tongue on one card catching on the rearwardly extending tongue on the card immediately in front when the cards are given relative upward motion away from each other, the space between the tongues of a card being sufficient to permit enough of said relative motion between successive cards before their tongues catch, to expose enough surface at the front top of each card for the display of a heading on the card.

16. A card index system comprising a plurality of cards in a stack, said cards when in substantial alignment being unconnected to each other, and engaging means between successive cards in the stack located substantially above the middle of the cards, said engaging means limiting the upward motion away from each other from their position of alignment in the stack of the successive cards, the allowable length of said motion being sufficient to expose predetermined portions of successive cards.

17. A card index system as claimed in claim 10 having a thin sheet of material fastened to the front of the card over the opening in the card formed by bending back the material of the card for the rearwardly extending tongue, and a thin sheet of material fastened to the rear of the card over the opening in the card formed by bending forwardly the material of the card for the forwardly extending tongue.

18. A card index system comprising a plurality of cards in a stack, and engaging means between successive cards in the stack comprising tongues for the front and rear respectively, of the cards, the tongues being so spaced one above the other and short enough to have a vertical clearance between their free edges so that when the cards are in substantial alignment, the tongue on the front of one card is out of engagement with the tongue on the rear of the next succeeding card, the upward motion away from each other from their position of alignment in the stack of the successive cards being limited by the coming into engagement of the front and rear tongues.

MAX THEIMER. 70
